(57) **CLAIM**

The ornamental design for an air conditioning apparatus, as shown and described.

DESCRIPTION

FIG. 1 is a perspective view of a first embodiment of an air conditioning apparatus;

FIG. 2 is a first side view of the air conditioning apparatus of FIG. 1;

FIG. 3 is a second side view of the air conditioning apparatus of FIG. 1;

FIG. 4 is a third side view of the air conditioning apparatus of FIG. 1;

FIG. 5 is a fourth side view of the air conditioning apparatus of FIG. 1; and,

FIG. 6 is a top view of the air conditioning apparatus of FIG. 1.

1 Claim, 6 Drawing Sheets
